Primary Examiner — Jae Liang*Assistant Examiner* — Christopher Torma(74) *Attorney, Agent, or Firm* — Eric Karich; Karich & Associates(57) **CLAIM**

The ornamental design for a pocket knife display organizer as shown and described.

DESCRIPTION

FIG. 1 is a perspective view of a pocket knife display organizer, in an open configuration, showing my new design;

FIG. 2 is a perspective view of the pocket knife display organizer, in a closed configuration, showing my new design;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The broken line showing of pocket knives is for the purpose of illustrating environmental structure that form no part of the claimed design. The broken line showing of the inside

(Continued)

drawer is for the purpose of illustrating portions of the pocket knife display organizer that form no part of the claimed design.

1 Claim, 5 Drawing Sheets
